COMBINATION SANDWICH PREPARATION AND REFRIGERATOR CABINET

Anthony R. Costantini, Lafayette Hill, and Anthony Di Angelus, Manoa, Pa., assignors to Victory Metal Manufacturing Corp., Plymouth Meeting, Pa., a corporation of Pennsylvania

Filed Nov. 21, 1963, Ser. No. 77,523

Term of patent 14 years

(Cl. D67—3)

Fig. 1.

Fig. 2.

Fig. 4.

The dominant features of our design reside in the portions shown in full lines.

We claim:

The ornamental design for a combination sandwich preparation and refrigerator cabinet, as shown and described.
